UNITED STATES PATENT OFFICE.

JAMES REAGAN, OF PHILADELPHIA, PENNSYLVANIA.

BOILER AND OTHER FURNACE.

1,210,363.

Specification of Letters Patent. Patented Dec. 26, 1916.

Application filed May 5, 1916. Serial No. 95,705.

To all whom it may concern:

Be it known that I, JAMES REAGAN, citizen of the United States, residing at Philadelphia, in the county of Philadelphia and State of Pennsylvania, have invented certain new and useful Improvements in Boiler and other Furnaces, of which the following is a specification.

My invention relates to furnaces which are designed to automatically serve the fuel and to similarly remove the ashes and other residual substances. I have heretofore invented improvements in a furnace of this general type, as will appear by referring to my application, Serial #28,742, dated May 17, 1915, and to my Patent #1,171,803, dated February 15, 1916, in which are shown a hopper and an oscillatory fuel feeder, a stationary head block constituting the bottom of a coking zone, a grate having reciprocatory stepped hollow bars, a rest grate, and means for removing ashes from the furnace.

The present invention involves improved means for disposing of the ashes, and for sealing the discharge end of the furnace against the entrance of air other than that which is required for combustion and is admitted under proper control.

The invention also involves details of construction, as will hereinafter appear.

In the drawings Figure 1 represents a vertical longitudinal section of the furnace; Fig. 2 is a vertical transverse section on the line $x-x$ of Fig. 1; Fig. 3 is an elevation of the water beam that in part supports the bridge wall, a portion being broken away to show the water pipes therein; Fig. 4 is a sectional view showing parts of the actuating mechanism for the ash remover; Figs. 5, 6 and 7 are sectional views showing the ejector for the ashes (called an ash drawer), and the track plates on which it moves; Fig. 8 is a plan view showing in full and dotted lines the rest grate, the ash drawer and the actuating parts for said ash drawer.

A is the hopper; B, the oscillatory fuel feeder; C, the head block; D a grate bar; E the rest grate; F, the refractory arch.

The top step d of the grate is somewhat higher than the other steps, and the parts are so related that when the sections of the grate are fully retracted the rear faces of the head block and the top step of the grate coincide and admit of the uninterrupted de-

scent of such particles of fuel as fall over the edge of the head block. The particles that have lodged on the upper face of the step d when the grate bar was advanced are pushed off as the said faces are brought into coincidence.

The ash drawer G is composed of sections G' arranged in a transverse series and each section is an inverted hollow casting having slots g in its front and rear walls, in which are disposed loosely mounted or floating scrapers g' having holes g^2 , through which small retaining bolts g^3 , extend. Grooved rollers g^4 , carried by brackets and running on the tracks g^5 of a track plate g^6 , sustain and carry the sections. The sections are made unitary by bolts g^7 , extending through adjacent sides.

The ash drawer is actuated by pull rods H driven by appropriate mechanism. These pull rods are each pivoted at h to a pull piece h' having a square hole h^2 receiving a square rod h^3 that extends throughout the entire series of the sections G' of the ash drawer G, the adjacent walls of these sections being slotted from below at h^4 for its reception. The square rod h^3 is secured in place by pairs of lugs h^5 , each integral with a wall of one of the sections G' , to each of which pairs is bolted an ear h^6 of a filler-piece h^7 for the slots h^4 . The ear h^6 is of such dimension as to extend under the square rod h^3 from one lug h^5 to the other lug h^5 of the same pair. The pull rod H is operated by a drive shaft I carrying a loosely mounted drive gear i , which meshes with what I term an eccentric gear J mounted on a shaft j that carries cams (not shown) for operating the grate sections. The drive gear i is provided with a cutting disk i' keyed to the drive shaft at i^2 . A bolt i^3 connects the drive gear and the disk but this bolt under excessive load will be sheared off and avoid the breaking of other and more important parts of the mechanism.

A pitman K is connected at its upper end to a pin k carried by the eccentric gear J, and is connected at its lower end to a bell-crank lever L, which in turn is connected to the pull rod H by a pivot l . The bell-crank lever is mounted on a bracket l' . The pitman contains a telescopic joint the parts of which are respectively a sleeve k' , and a rod k^2 , which in the absence of a pin k^3 , works idly. When the pin however, is inserted the sleeve and the rod move in unison

and motion is transmitted throughout the entire train of mechanism, including pull rods H and the ash drawer G. The sleeve k' is slotted at k⁴ and a pin extending 5 through rod k² moves in these slots and prevents relative rotation of the parts. It also has the function of imparting motion to the sleeve k' in one direction. An encircling tube k⁵ covers the slots.

10 The rotation of the drive shaft I transmits an oscillatory motion to the bell-crank L, and a consequent reciprocatory motion to the pull-rod H and the ash drawer G. The amplitude of this motion is such as to cause 15 the ash drawer G to alternately retreat into the space G³ in the lower part of the bridge wall M and to advance a distance sufficient to force the ashes toward the ash pit which it eventually reaches by passing through the 20 space O under the back leg P of the grate. A protective sleeve Q, somewhat smaller than the space O, loosely surrounds the end of the pull-rod H and moves with said rod. This sleeve becomes full of ashes which 25 enhances the protection.

The ashes from the grate occupy the space behind the back leg P and seals the furnace at this point against the entrance of air at the rear end of the grate. Combustion is, 30 therefore, supported, as it should be, only by air entering the furnace through and between the grate bars, which is always under the control of the operator. I thus avoid extensive partial combustion of the fuel constituents and am able to attain complete combustion of measured quantities of fuel regardless of its quality and physical character. The action of the ash-drawer is confined substantially to its face area so that 35 40 the main body of ashes in the space above it being practically undisturbed remains as a perfect seal.

The ash-drawer G is grooved at the top and front for the retention therein of a protective body of ashes. I employ what I 45 designate water beams, R, R', one R, being placed at the base of the bridge wall and the other R' being used as a support for the rest grate. These water beams are made of 50 castings containing wrought iron pipes which I have found to be especially effective in resisting the intense heat of the furnace. The water beam R is especially useful in 55 preserving the proper sectional area of the space G³ in which the ash-drawer moves, which, if affected, will cause the retardation or stopping of the movements of said drawer. The bridge wall M contains a built 60 in arch S, and is in part supported by a back beam T. If necessary to repair the parts adjacent the ash drawer, the brick wall and the water and back beams below the arch S may be entirely and conveniently 65 removed and reassembled without disturbing the main body of the bridge wall.

The above described devices, and especially the ash-drawer and its associated parts, are of great importance as means acting cooperatively with a furnace containing my improved fuel feeder and coking chamber, although they are of much value in any furnace wherein air is likely to be improperly admitted at the rear end of the grate. The removal of ashes is also rendered certain.

75 The operation of my furnace is, as will be understood, under perfect control. The fuel is fed to it in a steady and regulated volume, the distillation of the fuel is gradual and certain, the supply of air is not excessive, the distribution of the air through the grate is uniform and combustion is unaffected by air admitted elsewhere, and the ashes are removed in such manner as to not interfere with the continual operation of 80 the furnace. I have found by extensive experiments that the ash removing device arranged as disclosed herein is effective in preventing combustion beyond the grate and confining it to its proper zone, and that difficulties heretofore experienced in the burning out of the parts behind the grate have 85 been entirely surmounted by the improvements in the ash removing device herein described.

90 Having thus fully described my invention what I claim, is—

1. The combination with an inclined grate adapted to discharge substantially the whole body of ashes from the rear end thereof, a 100 bridge wall separated from said grate so as to leave a space for the ashes delivered from said grate, and an ash-remover consisting of a reciprocating ash-drawer adapted to be retracted from and drawn through 105 the lower portion of said body of ashes and a floor for sustaining the ashes over which said ash-drawer reciprocates.

2. The combination with an inclined grate adapted to discharge substantially the whole 110 body of ashes from the rear end thereof, a bridge wall separated from said grate so as to leave a space for the ashes delivered from said grate, and an ash-remover consisting of a reciprocating ash-drawer having front 115 and rear floating scrapers, and adapted to be retracted from and drawn into the lower portion of a body of ashes.

3. An ash-drawer, the body of which is adapted to move ashes and having front and 120 rear floating scrapers which have a free vertical movement independent of the drawer.

4. An ash-drawer composed of transversely disposed sections in combination with a bar extending through said sections 125 and pull rods connected to said bar.

5. An ash-drawer having a pull rod in combination with a loose protective sleeve for said rod.

6. The combination of a grate adapted to 130

discharge substantially the whole body of ashes from the rear end thereof, a bridge wall spaced therefrom, and an ash remover disposed below said bridge wall and adapted, when moved from below said bridge wall, to expel ashes from the space between the grate and bridge wall and a floor for sustaining the ashes over which said ash-drawer reciprocates.

10 7. A furnace having in combination a

grate, a bridge wall, and ash remover and water beams disposed on either side of the space between the grate and the bridge wall, the ash remover being contiguous to and protected by one of the said water beams. 15

In testimony whereof I affix my signature in presence of a witness.

JAMES REAGAN.
